[57] CLAIM

The ornamental design for a tray for attachment to a walker or the like, as shown and described.

DESCRIPTION

FIG. 1 is a perspective view of a tray for attachment to a walker or the like, showing my new design;

FIG. 2 is a top plan view thereof;

FIG. 3 is front elevational view thereof, the opposite side being a mirror image;

FIG. 4 is right side elevational view thereof, the opposite side being a mirror image;

FIG. 5 is a bottom plan view thereof; and

FIG. 6 is a cross-sectional view taken along line 6—6 of FIG. 2.

FIG. 1

FIG. 3

FIG. 2

FIG. 4

FIG. 5

FIG. 6
